(No Model.)

J. J. VAN BRIMER.

GATE.

No. 364,321.

Patented June 7, 1887.

UNITED STATES PATENT OFFICE.

JOSEPH J. VAN BRIMER, OF WARRENSBURG, OHIO.

GATE.

SPECIFICATION forming part of Letters Patent No. 364,321, dated June 7, 1887.

Application filed March 11, 1887. Serial No. 230,516. (No model.)

To all whom it may concern:

Be it known that I, JOSEPH J. VAN BRIMER, a citizen of the United States, residing at Warrensburg, in the county of Delaware and State 5 of Ohio, have invented a new and useful Improvement in Gates, of which the following is a specification.

My invention is an improved gate; and it consists in certain novel features of construction 10 and combination of parts, whereby the gate is adapted for use as either a swinging or sliding gate, and can also be elevated when desired, as will be hereinafter first fully described, and then pointed out in the claims.

15 In the annexed drawings, which fully illustrate my invention, Figure 1 is a perspective view of my improved gate, showing it rolled back and swung around out of the gateway. Fig. 2 is a side elevation of the gate closed, its 20 position when raised being shown in dotted lines; and Fig. 3 is a detail view of the device for supporting and guiding the gate in its movements.

Referring to the drawings by letter, A designates the gate, composed of the bars *a* and uprights *a'*, of ordinary form, connected in the usual manner.

B is the latch-post, of the usual construction, set in the ground, as shown. This latch-post B is provided at the proper height with 30 a longitudinal slot, *x'*, which is engaged by a latch-projection, *x*, secured to the end of the gate. In one side of the post I secure a hook, *b*, for a purpose presently specified.

35 The post B, it will be readily understood, is set in the ground at one side of the gateway, and at the other side of the gateway I set two posts, C C', in the ground a slight distance apart. These posts C C' are set in the ground 40 in such relative positions that a line connecting their centers will be at an angle of about forty-five degrees to the line of the gateway.

D D' are two angle irons or straps, which are secured at their opposite ends to the adjacent sides or edges of the posts C C', as shown. These straps are secured to the posts at a suitable distance apart and at any convenient height. A swinging loop, E, is secured between these straps D D' by means of 45 50 pivot-pins *e*, which are inserted through the said straps and the upper and lower cross-

bars, *e'*, of the swinging loop. The outer edge of the lower cross-bar, or that edge which is nearer the latch end of the gate, is upturned, as shown at *e*², for a purpose presently described. An oscillating rhomboidal frame, F, is hung within the swinging loop E, and carries grooved rollers *f* at its outer ends. The rear roller is about on a plane with the upper end of the swinging loop, and bears on the 60 upper edge of one of the bars *a*, while the forward roller receives the lower edge of the same bar, as clearly shown. This frame F is hung within the loop E by means of a pin, G, which is passed through the sides of said loop 65 at their upper ends, and through slots *g* in the sides of the frame near their upper edges. At their lower edges the sides of the frame F are provided with ratchet-teeth *g'*, which engage the pawl or upturned edge *e*², to hold the 70 gate at any desired elevation.

In operation the gate is rolled back about half-way across the gateway, and is then swung around to the side of the road, as will be readily understood from Fig. 1. When it is 75 desired to raise the front end of the gate to take up sag, to clear snow and ice, or to allow small stock to pass while keeping larger stock back, it is necessary only to raise the front end of the gate, (and rest it on the hook *b*), when 80 one of the ratchet-teeth *g'* will engage the pawl *e*² and hold the gate in its elevated position, at the same time allowing it to be rolled backward and swung around, as will be readily understood. When it is desired to lower the 85 gate, a slight upward pressure applied to the bottom of the gate at its rear end will disengage the ratchet-teeth from the pawl *e*², and the gate will immediately assume a horizontal position.

90 It will be readily seen that the gate while being elevated swings upon the pin G, and the slots *g* readily allow the raising of the rear end of the gate to disengage the ratchet-teeth from the pawl.

95 My gate is cheap, durable, and easily operated, and it is thought its advantages will be readily appreciated without being referred to in detail.

Having thus described my invention, what 100 I claim, and desire to secure by Letters Patent, is—

1. The combination of the stationary posts, the swinging loop supported by and between the posts, and the oscillating frame suspended at its upper end within the loop, and having 5 its lower end disconnected from but engaged by the lower portion of the loop, substantially as and for the purposes set forth.

2. The combination, with the gate-posts, of the swinging loop supported by and between 10 the posts, the lower cross-bar of the loop having a pawl or upturned edge, and an oscillat-

ing frame carrying the gate hung within the loop and having a series of ratchet-teeth on its lower edge to engage the pawl at the lower end of the loop, substantially as specified. 15

In testimony that I claim the foregoing as my own I have hereto affixed my signature in presence of two witnesses.

JOSEPH J. VAN BRIMER.

Witnesses:

JAMES E. WHITE,
WILLIAM J. DAVIS.
